UNITED STATES PATENT OFFICE.

ACHILLE LÉON FRANÇOIS WATTÉL, OF SÈVRES, FRANCE.

VALVE-GEAR FOR INTERNAL-COMBUSTION ENGINES.

1,303,748.

Specification of Letters Patent. Patented May 13, 1919.

Application filed April 13, 1918. Serial No. 228,493.

To all whom it may concern:

Be it known that I, ACHILLE LÉON FRANÇOIS WATTÉL, civil engineer, a citizen of the Republic of France, residing at 18 Avenue 5 Henri Renault, in Sèvres, Department Seine-et-Oise, France, have invented new and useful Improvements in Valve-Gears for Internal-Combustion Engines, of which the following is a specification.

10 The present invention relates to that kind of internal combustion engine working on the four-stage cycle principle, wherein the valve-gear is essentially composed of a piston-valve, the inlet of the combustible mixture and the outlet of the spent gases being 15 effected by means of such valve.

The main object aimed at by the invention is to provide a construction by which all reactions due to the effect of suction, compression 20 or explosion upon the piston-valve are obviated.

The characteristic feature of the invention resides in that the piston-valve is balanced.

A further peculiarity of this arrangement 25 is that the piston-valve is relieved of all shocks resulting from its contact with the cam used for operating it. Furthermore, it presents this advantage that it brings about a rapid opening and closing of the suction 30 and exhaust ports.

Another object aimed at by the invention is to provide for automatically lubricating and readily cooling the piston-valve.

Finally, the construction provided in accordance 35 with the invention is such that the valve-gear can be easily and quickly taken apart and put together again.

The accompanying drawing illustrates, by way of an instance, a valve-gear designed in accordance 40 with the characteristic features of the invention.

Figure 1 is a vertical section.

Fig. 2 is a plan.

The piston-valve α , which slides in the 45 valve cylinder b , is formed with annular grooves a^1 , a^2 for causing the explosion chamber h to communicate with the inlet duct c and the exhaust duct d . In the inner wall of the valve-cylinder b is formed, in 50 the same horizontal plane as the duct b^2 issuing from the explosion chamber h toward the said cylinder, an annular groove b^1 , the ends of which issue into the said duct b^2 , so that when the piston-valve α 55 assumes the position illustrated in the drawing, the pressure or suction generated inside

the explosion chamber h is uniformly distributed around the circumference of the piston-valve, thereby balancing the same in a transverse direction. The piston-valve 60 comprises a cylindrical portion a^3 which assists in guiding it. The suction and compression effects exerted upon the piston-valve being thus uniformly distributed over the same, both axially by the grooves a^1 , a^2 65 and transversely by the groove b^1 , the said member is thus balanced at all times so that all reaction is avoided, friction is brought down to a minimum and the power necessary for operating it is reduced accordingly. 70

The piston-valve is operated from a suitably shaped cam e operated from the crank-shaft or in any other suitable way. This cam remains constantly in touch with the 75 roller a^4 at the lower end of the piston-valve α , so that all shocks are obviated in the operation of this latter.

The piston-valve may be so held in contact with its driving cam by means of a 80 spring, not shown, interposed between the top of the piston-valve and the bottom of the closing plug f for the valve-chamber b . But the said spring might be located differently.

In the piston-valve is formed a channel a^5 85 which enables the engine carter-case g to be put into communication with the top of the valve-chamber b . The orifice of this channel, which opens into the top of the said chamber, may be free or it may be equipped 90 with a downwardly closing valve a^6 so that it opens when the piston valve moves downward and closes when it moves upward. When the orifice is not equipped with any 95 valve and when, therefore, the top of the chamber b communicates freely with the carter-case g , the particles of lubricant in suspension in the air, produced by splashing in the said carter-case, are automatically carried into the top of the chamber b and 100 insure lubrication of the piston-valve. If, on the contrary, the orifice of the channel a^5 is closed by a valve a^6 , the latter, when closing during the upward motion of the piston-valve, produces at the upper part of the 105 chamber b , a compression which has for its effect to force the said piston-valve in contact with its cam e during its downward motion, without substantially reducing the volume of the oil fed to the inside of the 110 chamber. The top of the chamber b thus acts as a pneumatic buffer.

Independently of the fact that the channel a^5 feeds lubricant to the piston-valve, it also acts to establish a circulation of air, taking such air in a cool condition within the 5 carter-case g and bringing it in contact both with the inside and top of the piston-valve and a portion of the inner wall of the valve-chamber b .

The operation is as follows: The piston-valve a establishes a communication between 10 the explosion chamber h and the suction duct c , such communication continuing to exist during the whole of the suction stroke, corresponding to the first stage of the cycle. 15 The piston-valve then moves for cutting off the communication with the inlet c both during the compression stroke (second stage) and during the active stroke (third stage), after which it again moves for establishing 20 communication with the exhaust duct d during the whole time of the exhaust (fourth stage), whereupon the same action is repeated.

The position which the piston-valve assumes in the drawing is that which corresponds either to the compression stroke or to the explosion stroke. When the cam leaves the piston-valve, the latter moves downward either under the action of a spring if one is 30 used, or under the influence of the fluid compressed in the top of the valve-chamber b , the return of such fluid being checked by the valve a^6 .

The piston-valve being balanced, there is 35 no abnormal friction and therefore no substantial wear. The so to say supple, yet constant connection between the piston-valve and its operating cam being a permanent one, no shock occurs. The splashing provides the oil necessary for lubricating the 40 said piston-valve in that the particles of lubricant are carried along by the air passing through the channel a^5 and, finally, the same air acts as a cooling medium for the 45 valve-gear as a whole.

The valve-gear can be easily taken apart. It is sufficient to remove the plug f and with-

draw the piston-valve a , the latter not being positively connected to any mechanical member. 50

Finally, the valve-chamber b may be formed of a member applied to or integral with the engine cylinder.

Having now particularly described and ascertained the nature of my said invention 55 and in what manner the same is to be performed, I declare that what I claim is:

1. Valve mechanism for internal combustion engines comprising a cylindrical valve chamber provided with a closed top, and an 60 open bottom, with inlet and exhaust ducts and with a port opening into the piston chamber of the engine, said valve chamber being also provided with an annular groove registering with said port, a piston valve 65 provided with a pair of annular grooves separated by a central annular rib, and with a longitudinally perforated valve stem, a roller carried by the lower end of said valve stem, and a flap valve opening upward carried by the upper end of said valve stem and closing the opening therethrough as the valve moves upward, and a rotary cam engaging said roller, substantially as described. 70

2. Valve mechanism for internal combustion engines comprising a cylindrical valve chamber provided with a closed top, and an 75 open bottom, with inlet and exhaust ducts and with a port opening into the piston chamber of the engine, said valve chamber 80 being also provided with an annular groove registering with said port, a piston valve provided with a pair of annular grooves separated by a central annular rib, and with a longitudinally perforated valve stem, a cylindrical guide piece carried by said valve stem near its lower end, a roller carried by the lower end of said valve stem, and a flap valve opening upward carried by the upper 85 end of said valve stem and closing the opening therethrough as the valve moves upward, and a rotary cam engaging said roller, substantially as described. 90

ACHILLE LÉON FRANÇOIS WATTEL.
